GARMENT HANGER

Ivan F. Stalecup, Bloomfield, Ind.

Application December 13, 1944, Serial No. 567,978

2 Claims. (Cl. 223—96)

1

This invention relates to a garment hanger, and particularly to one which may be extensible to accommodate garments of different width shoulders, and which will also carry men's trousers or ladies' skirts, either with or without the coat or jacket.

A primary object of the invention is to provide an exceedingly simple structure which may be relatively low in production cost and yet which will be not only durable over long periods of usage, but will be entirely effective in supporting trousers or skirts as the case may be without leaving imprints of clamping members thereon.

A further important object of the invention is to provide a rounded or enlarged end on each side of the hanger to fit into the shoulder of the garment to be carried thereby so as to preserve the shoulder shape without distortion and without requiring pressing even though the garment is carried on the hanger for considerable periods of time.

These and other important objects of the invention, such as the extremely simple mode of operation, will become apparent to those versed in the art in the following description of one particular form of the invention as illustrated in the accompanying drawing, in which

Fig. 1 is a view in side elevation of a structure embodying the invention;

Fig. 2, a view in end elevation;

Fig. 3, a bottom plan view with center portions cut away;

Fig. 4, a view in side elevation of the structure shown in Fig. 1 but in an extended position;

Fig. 5, a top plan view; and

Fig. 6, a detail on an enlarged scale in bottom plan view and in partial section of one end portion of the hanger, in modified form.

Like characters of reference indicate like parts throughout the several views in the drawing.

An upper portion of the hanger is formed in any suitable manner to have a hook 10 and a pair of downwardly and outwardly extending arms 11 and 12. In the present showing, this upper part is made out of a single piece of wire bent around one portion against another at the hook end, as illustrated in Fig. 5, and then carried around and downwardly to a twisted portion 13 from which the ends of the wires extend in single formation to give the legs 11 and 12. To the leg 11 is attached in any suitable manner, such as by looping the end of the leg 11 therearound and twisting it around itself to form a hinge joint, a spring loop 14 herein shown as being substantially circular in contour.

2

This loop 14 extends normally diagonally downwardly and outwardly substantially in alignment with the leg 11 and from the lower end thereof, a leg 15 on the one side and 16 on the other side is carried substantially horizontally therefrom when the parts are in the positions indicated in Fig. 1. These legs 15 and 16 enter within tubes 17 and 18 to fit slidably therewithin in most instances. The loop 14, as well as the extending legs 15 and 16 being integral parts thereof are made of a spring material, such as spring steel, and the legs 15 and 16 are so formed that they normally will hold the tubes 17 and 18 one tangential against the other. Furthermore, these legs 15 and 16 as they leave the looped end 14 are bent inwardly one toward the other, Figs. 2 and 3, so as to provide an entering wedge formation under the loop 14 to serve as a guide for entrance of pieces of clothing therebetween such as is suggested by the dash lines, Fig. 1, representing the cuff ends of trousers.

The same construction is employed at the end of the leg 12 in that there is a loop of spring material 19 preferably hinged to the end of the leg 12 to slope downwardly and outwardly therefrom and to have the legs 20 and 21 extending from the lower portion thereof one toward the other and horizontally into the ends of the tubes 17 and 18. Since the upper portion of the hanger including the legs 11 and 12 extending from the twisted portion 13 are flexible, upward pull on the hook 10 will tend to pull the respective legs carried by the loops 14 and 19 inwardly within the tubes 17 and 18, and thereby reduce the overall effective length of the hanger. To retain the hanger in an extended position, such as is indicated in Fig. 4, the tubes 17 and 18 may at one end at least carry the thumb screws 22 and 24 to extend inwardly and abut the respective legs 20 and 21 appearing therewithin, whereby those legs will be held in extended positions with the legs 11 and 12 flexing as indicated in Fig. 4 to approach parallelism with the tubes 17 and 18.

The loops 14 and 19 not only serve as powerful springs but also are of sufficient diameter in themselves and are so sloped that they will fit within the shoulders of a coat or jacket carried on the hanger so as to support the shoulder areas sufficiently to retain the garments in proper shape. While it has been indicated above that the cuff ends of trousers may be entered between the bars 17 and 18, either end being usable, the waist band of ladies' skirts may be entered through either one of the loops 14 or 19 over the tubes 17 and 18 to have a skirt hang therebe-

tween. It is to be understood that the loops 14 and 19 have sufficient diameter to afford clearance therethrough of that part of the garment which will be carried above the tubes 17 and 18.

Where it is desired to dispense with any adjusting mechanisms, such as the thumb screws 22 and 24, a friction retaining device may be employed as indicated in Fig. 6 on either or both ends of the tubes 17 and 18. In this form, the tubes 17 and 18 may have end portions bent outwardly one from the other slightly, and then the legs 20 and 21, for example, when inserted into the tubes will frictionally be gripped therewithin on opposing sides of the tube particularly toward the ends thereof, so that the normal tendency for the effective length of the hanger to be reduced by upward pull on the hook 10 is avoided and any adjusted length can be maintained under this frictional engagement.

While I have herein shown and described my invention in the form as now best known to me, it is obvious that structural changes may be employed, particularly in the upper portion of the hanger and also in the extension adjustments, all without departing from the spirit of the invention, and I therefore do not desire to be limited to that precise form beyond the limitations as may be imposed by the following claims.

I claim:

1. A garment hanger comprising a hanger hook; a pair of arms each oppositely extending from the hook; a substantially U-shaped spring attached to each of said arms by the cross member between the legs of the spring, said legs sloping outwardly and downwardly, and bending back below said cross member directly into horizontally disposed positions to converge one toward the other to leave a V entrance therebetween in said horizontally disposed positions; and a straight line member interconnecting each pair of opposing legs; said straight members be-

ing elastically urged one against the other by said springs; said arms being elastic and normally sloping outwardly and downwardly whereby said spring members may be yieldingly, variably spaced, one from the other; and said legs and said straight line members being formed to have said interconnection be extensible and retractible.

2. A garment hanger comprising a pair of straight line bars normally horizontally disposed side by side; a bar end member fixed to the end of each of said bars and extending laterally outwardly one from the other substantially within the horizontal plane of said bars, to form V openings therebetween at the respective ends of said bars; an arcuate, ring-like member, open on one side to have a leg from each side of that opening bent around acutely under said arcuate member and diagonally inwardly to merge one leg with the outer end of one of said bar end members and the other leg with the outer end of the other of said bar end members at one end of said bars, whereby the arcuate member is supported entirely above and inclined inwardly, and upwardly from the said bar ends; a second like arcuate member connecting and supported by said bar end members at the other of said bar ends; and a hanger interconnected with said arcuate members.
